United States Patent Office

Des. 192,200
Patented Feb. 6, 1962

192,200

HEATER

Murray Wilhoite, Nashville, Tenn., assignor to Temco, Inc., Nashville, Tenn., a corporation of Tennessee

Filed Dec. 9, 1960, Ser. No. 63,168

Term of patent 14 years

(Cl. D81—10)

Fig. 1.

Fig. 2.

Fig. 3.

Fig. 4.

Fig. 5.

Fig. 6.

FIGURE 1 is a front elevational view of the heater embodying my new design;

FIGURE 2 is a side elevational view of the heater embodying my new design;

FIGURE 3 is a top plan view of the heater embodying my new design;

FIGURE 4 is a fragmentary view of the screen portions of the heater;

FIGURE 5 is a fragmentary view of the louvered portions of the heater; and

FIGURE 6 is a section view taken substantially along line 6—6 in FIGURE 1.

It is to be understood that louvers and perforations, fragmentarily shown in FIGURES 1 and 2 for convenience of illustration only, cover the entire areas as indicated.

I claim:

The ornamental design for a heater, substantially as shown and described.
